UNITED STATES PATENT OFFICE

FRITZ STRAUB, OF BASEL, AND HERMANN SCHNEIDER, OF RIEHEN, NEAR BASEL, SWITZERLAND, ASSIGNEES TO FIRM: SOCIETY OF CHEMICAL INDUSTRY IN BASEL, OF BASEL, SWITZERLAND

AZO-DYESTUFFS CONTAINING CHROMIUM AND PROCESS OF MAKING SAME

No Drawing. Application filed November 5, 1931, Serial No. 573,300, and in Switzerland November 14, 1930.

The present invention relates to the manufacture of new azo-dyestuffs containing chromium. It comprises the process of making these dyestuffs as well as the new dyestuffs themselves.

By this invention valuable new dyestuffs containing chromium are obtained by heating in an aqueous solution a mixture of a chromium compound with at least one o-hydroxy-azo-dyestuff, which chromium compound is capable of forming complex chromium compounds, and which mixture contains at least two o-hydroxy-azo-dyestuffs, of which at least one is an azo-dyestuff from a 1-diazo-2-hydroxynaphthalene - 4-sulfonic acid and a naphthol, in presence of a proportion of alkali metal ions which neither have a salting out action on the dyestuff, nor unfavorably influence the tinctorial properties of the product, and then evaporating the reaction solution.

The new dyestuffs containing chromium may be regarded as intermediate products of the hitherto known chromium compounds. They are sensitive towards dilute mineral acids in that they partly precipitate for instance in a dye-bath containing the usual quantities of sulfuric acid, and do not, therefore, yield fast dyeings from such a bath. They are further characterized by such an easy solubility in water that they are incapable of being precipitated from the reaction solution by means of a saturated solution of common salt. They must therefore, if necessary after filtration, be obtained by evaporation of the reaction solution, preferably in a vacuum.

The present chroming process is carried out in such a manner that the mixture of the chromium compound with the o-hydroxy-azo-dyestuffs is heated in an aqueous medium. As chromium compounds which are capable of forming complex chromium compounds the usual agents yielding chromium may be used, such as chromium chloride, chromium fluoride, chromium sulfate, chromium sulfite, chromium acetate, chromium formate, chromium hydroxide, a chromium salt of an aromatic sulfonic acid, or the like, or a mixture of any of these chroming agents.

Particularly good results are obtained when chromium oxalate alone or mixed with another chroming agent (for instance a mixture of chromium sulfate or chromium sulfite and chromium oxalate) is used.

Besides these chroming agents, an azo-dyestuff containing chromium, made in the usual manner or as described in British Patent No. 364,147 may also be used as a chroming agent.

The alkali metal ions exert on the properties of the complex produced a favorable influence in respect of solubility, exhausting and levelling capacity. The proportion of alkali metal ions should not be, on the one hand, too small, because otherwise the satisfactory properties of the complex are not attained, and, on the other hand, not too large, since otherwise they would salt out the dyestuff and influence unfavorably the dyeing properties of the complex. The proportion of alkali metal ions by means of which the best effect is obtained, must be determined in each case by experiment.

The proportions in which the dyestuffs used are to be mixed may vary within wide limits.

The good result of the chroming is, however, dependent not only on the chroming agent or the proportion of alkali metal ions, but also on other conditions, such as time, temperature, diluent and hydrogen ion concentration, under which the chroming occurs; these conditions can be varied in many ways and it is a matter of manipulative working to determine in each case the most favorable conditions.

The new chromium compounds can be used for dyeing animal fibers in the manner similar to that described in the copending specification Serial No. 482,155, filed September 15, 1930, i. e. conducting the dyeing operation first in weak acid baths, and then developing the dyeings by treatment in dye-baths of stronger acidity. The grey or black dyeings thus produced are fast, particularly to fulling and potting. In the second stage, i. e. the development of the dyeings, a new complex is formed on the fiber.

The new dyestuffs are useful not only for

dyeing animal fibers, but also for printing, for dyeing leather, and for coloring varnishes.

The following examples illustrate the invention, the parts being by weight:

Example 1

303 parts of the azo-dyestuff from nitrated 1-diazo-2-hydroxynaphthalene-4-sulfonic acid and β -naphthol of the formula

98.5 parts of dyestuff from 1-diazo-2-hydroxynaphthalene-4-sulfonic acid and α -naphthol of the formula

25.2 parts of the dyestuff from 4-nitro-2-diazo-1-phenol-6-sulfonic acid and 1-phenyl-3-methyl-5-pyrazolone of the formula

40 are together suspended in 8000 parts of water. There are added 22 parts of caustic soda solution of 30 per cent. strength and 34 parts of sodium formate followed by a solution of chromium-bisulfite of 4.4 per cent. strength, corresponding with 76 parts of Cr_2O_3 and a chromium oxalate solution containing 7.6 parts of Cr_2O_3 .

45 The whole is now heated and boiled for 2-3 hours while stirring, whereupon the chromium compound of the three dyestuffs is isolated by evaporation to dryness under diminished pressure. The product is a dark powder and dyes wool in an acid bath pure black tints of remarkable fastness. Grey tints are obtained if the dyeing is performed in dye-baths of weaker dyestuff concentration.

Example 2

50 Into 8000 parts of water are introduced 303 parts of the azo-dyestuff from nitrated 1-diazo-2-hydroxynaphthalene-4-sulfonic acid and β -naphthol, 98.5 parts of the azo-dyestuff from 1-diazo-2-hydroxynaphthalene-4-sulfonic acid and β -naphthol, and 25.2 parts of the azo-dyestuff from 4-nitro-2-diazo-1-phenol-6-sulfonic acid and 1-phenyl-3-methyl-5-pyrazolone.

55 After thorough intermixture, there are further added 80 parts of sodium formate, 45 parts of calcined sodium sulfite, followed by a chrome solution corresponding with 83.6 parts of Cr_2O_3 made by means of 95 parts of crystallized oxalic acid and 63 parts of hydrofluoric acid of 50 per cent. strength. While stirring well, the whole is brought to the boil and maintained boiling for 2-3 hours. The black violet solution of the chromium complex is then evaporated to dryness on the water-bath under diminished pressure. It 60 dyes wool in an acid bath pure black tints of good fastness.

65 If in this example there are used instead of the 303 parts of the azo-dyestuff from the nitrated 1-diazo-2-hydroxynaphthalene-4-sulfonic acid and β -naphthol 352.3 parts of this dyestuff, and instead of the 98.5 parts of the azo-dyestuff from 1-diazo-2-hydroxynaphthalene-4-sulfonic acid and α -naphthol there are used 49.3 parts of this dyestuff, the complex produced dyes wool black tints which are somewhat more reddish.

Example 3

70 303 parts of the azo-dyestuff from nitrated 1-diazo-2-hydroxynaphthalene-4-sulfonic acid and β -naphthol, 98.5 parts of the azo-dyestuff from 1-diazo-2-hydroxynaphthalene-4-sulfonic acid and α -naphthol, 25.2 parts of the azo-dyestuff from 4-nitro-2-diazo-1-phenol-6-sulfonic acid and 1-phenyl-3-methyl-5-pyrazolone are introduced into 8000 parts of water and there are added 68 parts of crystallized sodium formate, 75 parts of calcined sodium sulfite and then a 75 chrome solution corresponding with 83.6 parts of Cr_2O_3 and made by dissolving chromium hydroxide paste with aid of 63 parts of crystallized oxalic acid and 115 parts of sulfuric acid of 98 per cent. strength. After 80 heating the solution to boiling, it is maintained in this condition for 1½ to 2 hours and then the chromium compound is isolated by evaporation to dryness under diminished pressure. In an acid bath the dyestuff dyes 85 wool pure black tints of very good fastness.

85 In this example, the sulfuric acid used for dissolving the chromium hydroxide may be exchanged for the equivalent quantity of hydrochloric acid with a like result.

Example 4

90 86 parts of the complex chromium compound obtained as described in Example 1 of British Patent No. 364,147, are dissolved in 900 parts of water, 12.5 parts of the azo-dyestuff from nitrated 1-diazo-2-hydroxynaphthalene-4-sulfonic acid and β -naphthol are added and the whole is boiled for 4 hours in a reflux apparatus. The chrome complex 95

dyestuff is isolated by evaporating the solution under diminished pressure. It is a black powder, very easily soluble in water to a violet black solution. In an acid bath it dyes 5 wool black tints of good fastness.

Example 5

A dye-bath is prepared with 2000 parts of water, 6-8 parts of formic acid, which in the 10 dyeing can be distributed as desired, 3-4 parts of the chromium compound made as described in Example 1 of British Patent No. 364,147 and 0.5 part of the dyestuff from nitrated 1-diazo-2-hydroxynaphthalene-4-sulfonic acid 15 and α -naphthol. 100 parts of wool are entered at 0° C., dyeing is continued for $\frac{1}{4}$ hour and in the course of half-an-hour the bath is heated to boiling. This temperature is maintained for some time until the dyestuff is exhausted. Then 6-7 parts of concentrated sulfuric acid are added and boiling is continued 20 until the color tint is fully developed, which happens in about 1 hour. The wool is dyed deep black tints of very good fastness.

Example 6

A bath is prepared with 2000 parts of water at a temperature of 85-90° C. and 1 part of formic acid; 100 parts of wool are entered 30 and the liquor is circulated for a short time in a dyeing apparatus; there are then added a further quantity of 1-2 parts of formic acid and 7-8 parts of the chromium compound described in Example 1. Dyeing is continued 35 at the same temperature for about 10 minutes and then the bath is raised to the boil and boiled for 20 minutes. There are then added two parts of concentrated sulfuric acid diluted with water in the course of 10 minutes, and after a further 20 minutes 6 parts of concentrated sulfuric acid diluted with water 40 are added. The dyeing is developed by boiling for 1 hour. The wool is dyed black tints of very good properties of fastness.

What we claim is:—

1. A manufacture of chromiferous dyestuffs, wherein a mixture of a chromium compound with orthohydroxyazodyestuffs, which chromium compound is capable of forming complex chromium compounds, and which mixture contains at least two ortho-hydroxyazodyestuffs, of which at least one is an azo-dyestuff from a 1-diazo-2-hydroxynaphthalene-4-sulfonic acid and a naphthol, is heated 50 in an aqueous solution, and in presence of such a proportion of alkali metal ions as will neither serve to salt out the dyestuff, nor exert an unfavorable influence on the tinctorial properties of the product, and then evaporating the reaction solution to dryness.

2. A manufacture of chromiferous dyestuffs, wherein a mixture of a chromium compound with orthohydroxyazodyestuffs, which chromium compound is capable of forming complex chromium compounds, and which

mixture contains an azo-dyestuff from the nitrated 1-diazo-2-hydroxynaphthalene-4-sulfonic acid and a naphthol and an azo-dyestuff from the 1-diazo-2-hydroxynaphthalene-4-sulfonic acid and a naphthol, is heated in an aqueous solution, and in presence of such a proportion of alkali metal ions as will neither serve to salt out the dyestuff, nor exert an unfavorable influence on the tinctorial properties of the product, and then evaporating the reaction solution to dryness.

3. A manufacture of chromiferous dyestuffs, wherein a mixture of a chromium compound with orthohydroxyazodyestuffs, which chromium compound is capable of forming complex chromium compounds, and which mixture contains the azo-dyestuff from the nitrated 1-diazo-2-hydroxynaphthalene-4-sulfonic acid and β -naphthol and the azo-dyestuff from the 1-diazo-2-hydroxynaphthalene-4-sulfonic acid and α -naphthol, is heated 55 in an aqueous solution, and in presence of such a proportion of alkali metal ions as will neither serve to salt out the dyestuff, nor exert an unfavorable influence on the tinctorial properties of the product, and then evaporating the reaction solution to dryness.

4. A manufacture of a chromiferous dyestuff, wherein a mixture of the dyestuff containing chromium from the nitrated 1-diazo-2-hydroxynaphthalene-4-sulfonic acid and β -naphthol, with the dyestuff from the nitrated 1-diazo-2-hydroxynaphthalene-4-sulfonic acid and β -naphthol, is heated in an aqueous solution, and in presence of such a proportion of alkali metal ions as will neither serve to salt out the dyestuff, nor exert an unfavorable influence on the tinctorial properties of the product, and then evaporating the reaction solution to dryness.

5. The new chromium compounds which are obtained by heating a mixture of a chromium compound with ortho-hydroxyazodyestuffs, which chromium compound is capable of forming complex chromium compounds, 610 and which mixture contains at least two ortho-hydroxyazodyestuffs, of which at least one is an azo-dyestuff from a 1-diazo-2-hydroxynaphthalene-4-sulfonic acid and a naphthol, in an aqueous solution, and in the presence of 615 such a proportion of alkali metal ions as will neither serve to salt out the dyestuff, nor exert an unfavorable influence on the tinctorial properties of the product, and then evaporating the reaction solution to dryness, 620 which products are dark to black powders which are very easily soluble in water, and dye wool grey to black shades of very good fastness.

6. The new chromium compounds which are obtained by heating a mixture of a chromium compound with ortho-hydroxyazodyestuffs, which chromium compound is capable of forming complex chromium compounds, 625 and which mixture contains an azo-dyestuff

from the nitrated 1-diazo-2-hydroxynaphthalene-4-sulfonic acid and a naphthol and an azo-dyestuff from the 1-diazo-2-hydroxynaphthalene-4-sulfonic acid and a naphthol, 5 in an aqueous solution, and in the presence of such a proportion of alkali metal ions as will neither serve to salt out the dyestuff, nor exert an unfavorable influence on the tinctorial properties of the product, and then 10 evaporating the reaction solution to dryness, which products are dark to black powders which are very easily soluble in water, and dye wool grey to black shades of very good fastness.

15 7. The new chromium compounds which are obtained by heating a mixture of a chromium compound with ortho-hydroxyazodyestuffs, which chromium compound is capable of forming complex chromium compounds, 20 and which mixture contains the azo-dyestuff from the nitrated 1-diazo-2-hydroxynaphthalene-4-sulfonic acid and β -naphthol and the azo-dyestuff from the 1-diazo-2-hydroxynaphthalene-4-sulfonic acid and α -naphthol, 25 in an aqueous solution, and in the presence of such a proportion of alkali metal ions as

will neither serve to salt out the dyestuff, nor exert an unfavorable influence on the tinctorial properties of the product, and then evaporating the reaction solution to dryness, which products are dark to black powders which are very easily soluble in water, and dye wool grey to black shades of very good fastness.

8. The new chromium compound which is obtained by heating a mixture of the dyestuff containing chromium from the nitrated 1-diazo-2-hydroxynaphthalene-4-sulfonic acid and β -naphthol with the dyestuff from the nitrated 1-diazo-2-hydroxynaphthalene-4-sulfonic acid and β -naphthol, in an aqueous solution, and in the presence of such a proportion of alkali metal ions as will neither serve to salt out the dyestuff, nor exert an unfavorable influence on the tinctorial properties of the product, and then evaporating the reaction solution to dryness, which product is a black powder which is very easily soluble in water, and dyes wool grey to black shades of very good fastness.
